UNITED STATES PATENT OFFICE.

EDMUND B. DIKEMAN, OF CHICAGO, ILLINOIS.

SHAFT OR POLE SUPPORT.

SPECIFICATION forming part of Letters Patent No. 696,552, dated April 1, 1902.

Application filed December 5, 1901. Serial No. 84,722. (No model.)

To all whom it may concern:

Be it known that I, EDMUND B. DIKEMAN, a citizen of the United States, residing at Chicago, in the county of Cook and State of Illinois, have invented certain new and useful Improvements in Shaft and Pole Supports; and I do declare the following to be a full, clear, and exact description of the invention, such as will enable others skilled in the art 10 to which it appertains to make and use the same.

The invention relates to shaft-supports, and more particularly to a device to be attached to the stationary ears of the axle to which the 15 thill-iron is bolted and which will support the shafts in their elevated position when the vehicle is sheltered in a barn, stable, or under a shed and the horse detached.

The object of the invention is to provide a 20 device of this character which shall be simple of construction, durable in use, comparatively inexpensive of production, and which may be easily and quickly applied to and removed from the vehicle.

25 With this and other objects in view the invention consists of certain novel features of construction, combination, and arrangement of parts, which will be hereinafter more fully described, and particularly pointed out in the 30 appended claim.

In the accompanying drawings, Figure 1 is a perspective view of a fragment of a vehicle-axle, one of the shafts connected thereto, and my invention, the latter being shown to support the shaft in an elevated position. Fig. 35 2 is a detail view of the support removed, and Fig. 3 is a longitudinal sectional view through the same.

In the accompanying drawings, 1 denotes 40 the ears attached to the axle and between which the thill-iron 2 is pivoted by a bolt 3.

4 denotes the shaft-support, which consists 45 of a plate 5, having a recess 6, which snugly fits one of the ears. The flange 7 and the swell portion 8 bear against the edges of the ear and prevent the plate from twisting when it supports the weight of the shafts. The bolt 3 is passed through the aperture 6^a and a nut placed upon the bolt, thus securely 50 clamping the plate 5 in an upright position.

In the upper part of the plate is formed a vertical chamber or slot 9, in which the arm 10 is adapted to lie when the device is not in use. The said arm has a loose pivotal and

sliding connection with the plate through the 55 medium of the pin 11 and the slot 12, formed in the arm. Communicating with the upper end of the chamber 9 is an opening 13, through which the arm 10 is adapted to slide after being swung up to a horizontal position or at 60 right angles to the plate 5. When in this position, the arm is adapted to lie in the path of movement of the shaft, so that when said shaft is elevated and the arm is swung up and slid under the same the shaft will be supported in its elevated position. To hold the 65 arm in its chamber when not in use, I place a bow-spring 14 in the chamber between the arm and one of the side walls of the chamber and secure the same in position by passing 70 the pin 11 through it. When the arm is seated in its chamber, the tension exerted by the spring will cause said arm to remain in its closed position and prevent any rattling or noise. The lower end of the arm is formed 75 with a finger-piece 15 to enable the operator to readily swing the arm up.

From the foregoing description, taken in connection with the accompanying drawings, the construction, mode of operation, and advantages of the invention will be readily understood without requiring a more extended explanation.

Various changes in the form, proportion, and details of construction may be made within 85 the scope of the invention without departing from the spirit or sacrificing any of the advantages thereof.

Having thus described my invention, what I claim, and desire to secure by Letters Patent, is—

A shaft-support consisting of a vertical plate, the lower end of which is adapted to be secured to the fixed ears of the coupling, the upper portion formed with a vertical chamber, and an arm having a longitudinal slot 95 engaging a pivot-pin in said chamber and adapted to seat in said chamber when not in use and a spring secured in said chamber and adapted to hold said arm in its seat or chamber, substantially as set forth. 100

In testimony whereof I have hereunto set my hand in presence of two subscribing witnesses.

EDMUND B. DIKEMAN.

Witnesses:

MAUDE B. SMITH,
JOHN OSTERHOUSE.
